ATTORNEY

UNITED STATES PATENT OFFICE.

WILLIAM FINKELSTEIN, OF PHILADELPHIA, PENNSYLVANIA.

HANDLE.

Application filed March 29, 1928. Serial No. 265,633.

My invention relates to new and useful improvements in handles such as are used on hand-bags, traveling bags, suit cases, valises and the like and has for its general object the provision of a handle with a reinforcing cap which shall be strong, easy to manufacture and to assemble and also the provision of a method of making the same.

Handles for valises and the like may be considered as being made up of the following three major parts:

1. A core of some substance having a high tensile strength, usually a metal wire. This core usually ends in a loop through which the ring which joins the handle to the bag passes.
2. A filler covering this core, and
3. A cover encompassing the assembly of the core and filler.

It has long been the practice to provide handles for valises and the like with caps. The caps in such cases serve either to beautify the handle or to keep the leather at the ends of the handle from fraying, or both.

In the handles of this type now in general use, there is no positive connection between the core of the handle and the cap. In such cases, where the handle is joined to the bag by means of rings which pass through a loop in the core or the end of the handle, the pressure due to the weight of the bag is taken up by the handle per se. No part of the pressure is borne by the cap.

Several handles have been designed in which the cap is joined to the handle at one point and at another to the ring connecting the handle to the bag. These are open to many objections, the chief among which are the expense and difficulty of assembly, the fact that it is difficult to make the cap fit tightly, and the further fact that even when it has been made to fit, it will work loose.

It is one of the objects of this invention to produce a handle having a cap directly attached to the core of the handle which assembly shall not only be free from the objections to the handles now in use, but shall have advantages not possessed by them.

Another object is to provide a handle with a cap, which cap shall be attached positively and directly to the metallic core of the han-

dle and which shall be easy to manufacture and assemble.

Another object is to provide a method of making the said handle.

Another object is to construct a handle having a cap which cap shall be joined at the same point to both the core of the handle and the ring joining the bag to the handle.

Another object of my invention is to construct a cap, which cap shall primarily take the pressure due to the weight of the bag.

Another object of my invention is to provide a handle having a cap, which cap shall be positively and directly attached to the core of the handle.

Another object of my invention is to provide a handle having a cap, which handle shall be directly attached to the core of the handle without the use of rivets, screws, or auxiliary loops.

Another object of my invention is to produce a handle having a cap, which cap shall be attached to the core of the handle in such a manner that the place of attachment of the cap to the core of the handle also serves as the point through which the ring joining the handle to the core extends and on which the said ring bears.

Another object is to provide a handle with a cap, the top of which cap shall be so constructed as to eliminate any sharp edges at the point where the top of the cap ends.

These and other objects and advantages are attained by means of a combination and arrangement of parts to be hereinafter described and claimed. In order that the same may be better understood, reference is had to the accompanying drawing forming a part of the specification.

In the drawing:
Figure 1 is a side view of the assembly of the ferrules and wire, showing the core assembled and the first step in the process of making the handle.

Figure 2 is a top view of the same.
Figure 3 is a top view showing the assembly of the core, the filler and the leather cover, before the latter is wrapped to cover the handle.

Figure 4 shows the completed handle in-

cluding the caps and attaching ring, parts being broken away to more clearly bring out certain details of construction.

Figure 5 is a top view of the same.
5 Figure 6 is a side view of another modification.

Figure 7 is a side view of still another modification.

Figure 8 is a top view of the ferrule or 10 nodule.

Figure 9 is a front view of the same.
15 Figure 10 is a top view of the cap before its attachment to the handle.

Figure 11 is a front view of the same.
15 Figure 12 is a section through the handle after the filler is inserted between the strands of the core and illustrates the second step in the method of making the handle.

Figure 13 is a section through the assembly 20 of the core and the filler after the latter had been bent to form two parts and illustrates the third step in the method of making the handle.

Figure 14 is a section through the assembly 25 of the core, filler and cover after the latter had been stitched and shows the fourth and fifth steps in the method of making the handle.

Figure 15 is a section through the completed handle on the line 15—15 of Figure 4 30 and shows the next step in the method of making the handle.

Figure 16 is a section on line 16—16 of Figure 7 and shows the internal structure of 35 a modification.

Figure 17 is a section on the line 17—17 of 40 Figure 4 and shows the cap and ferrule structure, the manner in which they are assembled and the flange at the top of the cap.

Figure 18 is a section taken on line 18—18 of Figure 7, showing the manner in which 45 the cap is joined to the core in another modification.

Figure 19 is a section on line 19—19 of Figure 18.

Figure 20 shows the assembly of the ferrule and cap.

Figure 21 is a section taken on line 21—21 of Figure 20.

Figure 22 is a section taken on line 22—22 of Figure 20.

Referring more specifically to the drawing, 1 denotes a handle which is made up of metallic core, 2, and an inner covering or filler 3, 55 an outer covering 4 and caps 5.

The metallic core 2 is composed of metallic wire 6 looped over the outside surface 18 of the annular ferrules or nodules 7 as shown at 8 to form two distinct strands 9. 60 The ferrules 7 are tubular and have flanged edges 10. The flanges may be omitted if desired.

Placed between the strands 9 of the wire 6 is a filler 3 which may be made of cardboard 65 or any other material used as a filler.

Covering the assembly of the filler and metallic core is a covering 4, which may be leather, leatheroid or any other material used as a cover.

The assembly of the metallic core, the 70 filler and the covering will herein be designated as the handle assembly.

Directly attached to the ferrules 7 in a manner hereinafter more specifically set forth and covering the ends 22 of the handle 75 assembly are caps 5.

The caps 5 previous to their attachment to the handle assembly are merely cup shaped pieces of metal or any other hard substance having an outer shell 12, open at the top 13 80 as shown in Figures 10 and 11. After being attached to the ferrules 7 the cups 5 have holes 15 therein. Flanges 16 extend inwardly from the said holes and terminate within and bear against the inside surface 17 of the annular 85 ferrules 7, thus positively locking the caps 5 to the ferrules 7. The caps 5 are also flanged at the top 13 to form flange 23 which bites into the handle 1, thus causing the caps to be more firmly attached to the said handle and 90 further eliminating the sharp edges at the point where the cap ends.

The method of assembling the above described handle is as follows:—

The wire 6 is looped around the outside 95 surfaces of 18 of the annular ferrules 7, forming two parallel strands 9, the ends tied as shown at 19, wire being made the length necessary for the handle. (See Figures 1 and 2.) The filler 3 is now placed between the 100 strands 9 and treated and bent to form two parts, 21 and 22, in the manner well known in the art. (See Figures 3, 12, 13 and 14.)

The filler and metallic core are now covered with the covering 4, the ends 20 of which are sewed together as at 11. (See Figure 14.) The ends 20 are tucked between the two parts 21, 21 of the filler 9 and the entire handle assembly treated, shaped and pressed in the manner now well known in the art, to assume 110 its final shape. (See Figures 4 and 15.) Caps 5, without holes, are now fitted around the ends 22 of the handle assembly. Each end bearing the cap is now successively placed in a machine which punches holes 15 in the 115 said caps at a point registering with the hollow interior 24 of the annular ferrules 7. The metal which is punched out forms flanges 16 which enter the hollow portion 24 of the annular ferrules 7 and bear against the inside surface 17 of the said ferrules. The handle is then placed in another machine which forms the flanges 23 in the top of the 120 caps 5, thus forcing the top 13 of the cap 5 to more firmly grip the handle and also eliminating the sharp edges at the points where the cap ends.

The handle is attached to the bag, valise, suitcase, hand-bag and the like by the conventional rings 30 or other attaching means 130

which extend through the annular ferrules 7 or the looped ends 28. The rings bear directly against the flange portions 16 of the cap 5 which are within the interior 24 of the 5 ferrules 7.

It is to be understood that the above disclosure is by the way of illustration only and not by the way of limitation.

Variations can be made both in the materials used for any specific part of the handle as well as the specific structure of the core or the structure of the handle without departing from the spirit of my invention, the essence of which consists in providing a handle having a cap which is positively and directly attached to the metallic core.

For instance, instead of using a handle having a metallic core of the type shown in Figure 1, a handle 26 having a core of flat 20 steel wire 27 with looped ends 28 may be used. (See Figures 6, 18 and 19.) The filler and covering may be placed on this handle in the manner outlined above or may be wrapped thereon in the manner well known in the art. 25 After the handle is assembled the caps 5' are fitted thereon in the manner outlined above. The ends of the assembled handle are successively placed in the proper machine and the holes 24' are punched in the caps 5' simultaneously forming flanges 16' which extend into the inside surface 29 of the looped end 28. The handle is finished by forming the flange 23' in the top of the cap 5' in the same manner as the flange 23 is made. The looped 30 end in this modification has the same function as the annular ferrule 7.

Or, the metal core may be a single wire as shown in Figure 6, at the ends of which ferrules or nodules are attached.

40 Or, variations may be made in the size and the shape of the looped ends which are the equivalent of ferrules 7, or in the shape, structure or material used for the metallic core, or in the shape, size, structure or material 45 used for the ferrule per se, or in the manner of attaching the ferrule to the metallic core, or in the types of flange 16, 16' or 23, 23'.

It is to be further understood that the terms used in the claims which are herein attached are to be interpreted in the light of the following definitions:

50 Nodule or ferrule is herein used to designate any type of hollow tube-like structure to which wires of the metallic core may be attached.

Loop is herein used to designate broadly a hollow tube-like body formed at the terminals of the core by a loop turn or twist in the material of which the core is made.

Bulb is herein used to designate broadly a 60 hollow tube-like structure at the core terminals. This may be a ferrule made of a separate piece of material and attached to the core at its terminals or it may be a loop in the core per se.

65 Flange, or excrescence, is herein used to designate a piece of metal attached to another piece and extending from it.

Having described my invention, what I claim is:

70 1. A handle for hand-bags, traveling-bags, suitcases, valises and the like consisting of a core, ferrules attached to the terminals of the said core, a filler covering said core and a cover encompassing the said filler; means for protecting the free ends of the said assembly of the core, filler and covering, the said means consisting of a cap covering each of the said ends; and means for positively joining the said cap to the said core, the said means consisting of the said ferrules and flanges carried by the said caps, the said flanges extending into the said ferrules.

75 2. A handle for hand-bags, traveling-bags, suitcases and the like consisting of a core terminating in bulbs, a filler, a cover encompassing the said core and filler, and caps directly attached to the said core and encompassing the assembly of the said core, filler and cover; means for attaching the said caps directly and positively to the said core, the said means consisting of the said bulbs and flanges carried by the said caps, the said flanges extending into and terminating within the said bulbs; and means for simultaneously attaching the said caps and handle directly to the said hand-bag, suit-case, traveling-bag, valise or the like, the said means consisting of the said bulb and an opening in each of the said caps, the said opening in each of the said caps registering with the opening in the said bulbs.

80 100 105 3. A handle for hand-bags, traveling-bags, suit-cases, valises and the like consisting of a core terminating in bulbs and a body portion covering the said core; means for protecting the free ends of the said assembly of the said core and body portion, the said means consisting of a cap covering each of the said ends; and means for positively joining the said cap to the said core, the said means consisting of each of the said bulbs and flanges carried by the said caps, the said flanges extending into and terminating within the said bulbs.

110 In testimony whereof I hereby affix my signature.

WILLIAM FINKELSTEIN.
